UNITED STATES PATENT OFFICE

2,028,158

METHOD OF INCORPORATING EXTREMELY
VISCOS LUBRICANTS IN ROPE MATE-
RIAL

Walter D. Hodson, Beverly Hills, Ill.

Application November 2, 1934, Serial No. 751,245

2 Claims. (Cl. 117—2)

This invention relates to an improved method of and apparatus for incorporating extremely viscous lubricants in rope material.

In my co-pending applications Nos. 636,094 filed October 3, 1932, 637,007 filed October 10, 1932, and 744,426 filed September 17, 1934, are disclosed lubricants for wire ropes and rope materials in general. Many of these lubricants are of an extremely heavy nature and they are all viscous, tenacious, fibre-containing, adhesive lubricants. The incorporation of lubricants of this class into rope material has proved extremely difficult. Lighter lubricants which will seek their own level by gravity may be readily incorporated by means of the apparatus disclosed in the Kinder Patent No. 1,969,563, but proper apparatus for the incorporation of heavier and more viscous lubricants has heretofore been lacking.

By means of the present invention a method is provided for incorporating the most viscous lubricants into rope material, including vegetable fibres, either before or after initial stranding, and into wire ropes prior to stranding.

The invention is illustrated in the drawings in which—

Fig. 1 is a broken side elevation of the lubricating apparatus including the stranding machine for stranding wires;

Fig. 2 is a plan view broken away with the right-hand portion of Fig. 1;

Fig. 3 is a side elevation broken away of that portion of the device adjacent to the closing die, showing a modified form of scraper;

Fig. 4 is a section along the line 4 in Fig. 3;

Fig. 5 is similar to Fig. 3, showing a funnel shaped scraper;

Fig. 6 is a section along the line 6 in Fig. 5;

Fig. 7 shows a side elevation similar to Fig. 3 in which both an interior and exterior scraper are used;

Fig. 8 is a section along the line 8 in Fig. 7;

Fig. 9 shows a modified form in which the die itself is made bell-mouthed to provide an integral scraper;

Fig. 10 is a section along the line 10 in Fig. 9.

The first ten figures relate to the lubrication of wires prior to their incorporation into wire rope strands. Figures 11 to 17 represent apparatus for the lubrication of vegetable fibres prior to the formation of the fibres into twine.

Fig. 11 is a broken side elevation partly in section of a conventional twining machine feeding device or nippers and illustrates a method of incorporating the lubricant in such device;

Fig. 12 is a side elevation broken away of an

other form of apparatus in which no closing die is used;

Fig. 13 is an end view of the same apparatus;

Fig. 14 is a broken side elevation partly in section of a twining machine in which the lubricant is introduced inside of a yieldable funnel;

Fig. 15 is a sectional view along the line 15 in Fig. 14 showing the yieldable portion of the funnel;

Fig. 16 is a view corresponding to Fig. 14 in which the funnel or scraper is provided with springs to provide the necessary tension;

Figs. 17 and 18 show apparatus for the stranding of twine.

Fig. 17 is a broken side elevation partly in section showing a closing die with a lubricant nozzle adapted to eject lubricant within a closed compartment;

Fig. 18 is a similar view in which the mouth of the die is made funnel shaped to provide the desired scraping action.

The general form of operation of the invention is illustrated in Figure 1 in which 1 is a lubricant tank adapted to withstand a pressure of 100 pounds or upwards; 2 is a pipe leading to an air supply; 3 is a valve-controlled vent for the tank; 4 is a lubricant ejector nozzle controlled by valve 5 and connected by pipe 6 to the lubricant supply. The lubricant nozzle is placed directly over the wires 7 at a point where they are converging toward the closing die 8. It will be understood that the entire group of wires 7 is rotating rapidly beneath the ejector nozzle 4.

The lubricant is ejected from the tank 1 by air pressure supplied through the pipe 2 and the lubricant passes out through the nozzle 4 under the wires 7, where it tends to form a doughnut about the revolving wires. A vertical wiper 9 is provided which forces the lubricant inside of the wires so that the lubricant thoroughly surrounds and coats them. Excess lubricant is forced from the wires at the mouth of the closing die 10 and may be caught below the apparatus. The strand 11 issuing from the opposite side of the die is thus thoroughly impregnated with the lubricant.

In Figs. 3 and 4 a modified form of wiper 9a is shown which is made concave to provide a wiping action upon more wires at one time. This idea is further carried out in Figs. 5 and 6 in which the wiper completely incloses the wires to form a funnel 9b, provided with a hole in which the lubricant nozzle 4 is fitted.

With certain lubricants it is advisable to have an internal wiper as well as an external one, and Figures 7 and 8 illustrate such a device in which

there is an internal funnel-shaped wiper 12 and an external concave wiper 9c.

A still further modified device is shown in Figures 9 and 10 in which the closing die 8a is provided with a funnel-shaped mouth 13 which acts as a wiper. In this instance the area of the funnel is so small that the wires and the lubricants themselves act as an internal wiper and put the whole of the lubricant under great pressure.

10 In the case of vegetable fibres, the strands may be made from yarns and strands laid together to form a rope, or the two steps may be carried out on one machine. In either event the yarns are first formed from the fibres on a spinning machine. It may be desirable to incorporate the lubricant either at the time of the formation of the yarn, or at the time of the formation of the strands from the yarn.

15 In Figure 11 is shown a conventional form of spinning die 14 in which the fibres 15 enter the die when they are removed as yarn 16, undergoing a twisting motion during their passage. In this form of operation it is preferred to lubricate the yarn through the nozzle 4b which is drilled through 20 the die 14 and ejects lubricant into the funnel-shaped mouth 17 of the die. In this instance the walls of the die act as a wiper.

25 A modified form of procedure in connection with spinning machines is shown in Figures 12 and 13 in which the lubricant is ejected within the body of the fibres 15 prior to their entry into a closing die not shown. In case of vegetable fibres the natural curl of the fibres is sufficient to carry the lubricant to the closing die which then 30 acts as a wiper. However, in some instances it may be desirable to provide a wiper as shown in Figures 14, 15 and 16. In Figure 15 a funnel-shaped wiper 18 is provided in which the right-hand portion is made yieldable as shown in Figure 35 15, by overlap of a metallic portion for example. A similar wiper 19 is caused to press against the fibres 15 by the springs 20, as shown in Figure 16.

40 Where it is desired to lubricate the yarns, the lubricant may be injected into the twining yarns just prior to their entry into the closing die 8 as illustrated in Figure 17. In this instance it is preferred to wholly inclose the lubricant and 45 yarns within a wiper 21 so that the yarns pass

through a substantially continuous body of lubricant under high pressure.

Figure 18 shows a modified form in which the mouth 22 of the closing die is made funnel shaped and thereby maintains a body of lubricant under great pressure therein. 5

In general the lubricant, being applied at a time when the effective volume of the fibres is becoming rapidly less, is maintained under great pressure, and the effect of the wiper is to maintain a 10 continuous body of lubricant within and about the fibres which is maintained under tremendous pressure through which all of the fibres must pass.

15 As used herein the term "fibres", generically applied, covers not only vegetable fibres but any rope constituent which is to be made into a larger unit. For instance it covers the wires before stranding and the yarns before stranding, and also strands of wires or fibres being built into a rope. 20

25 In view of the extremely viscous character of the lubricant, high pressures are preferred in the lubricant tank 1. Normally a pressure of 100 pounds or thereabouts would be sufficient, but it may be advisable to step this up, through a piston hydraulic pump, or extrusion process, if desirable, to as much as a thousand pounds.

30 The foregoing detailed description is given for clearness of understanding only, and no unnecessary limitations should be understood therefrom, but the appended claims should be construed as broadly as permissible in view of the prior art.

I claim:

35 1. The method of applying a viscous, tenacious, fibre-containing adhesive lubricant unable to seek its own level by gravity to rope material, which comprises forcing the lubricant under high fluid pressure onto moving rope fibres while rapidly drawing the fibres together, and correlating the rate of flow of lubricant and the speed of the 40 fibres to maintain a continuous body of lubricant under pressure through which the rope fibres are forced to pass.

45 2. The method as set forth in claim 1, in which the rope fibres are brought together in a confined space, and the lubricant is held therein under high pressure by its adhesion to the moving rope fibres.

WALTER D. HODSON.
